UNITED STATES PATENT OFFICE.

CLAUD A. REESE, OF BOWLING GREEN, FLORIDA.

DIRECTION-INDICATOR.

1,195,088.

Specification of Letters Patent. Patented Aug. 15, 1916.

Application filed January 29, 1915. Serial No. 5,081.

To all whom it may concern:

Be it known that I, CLAUD A. REESE, a citizen of the United States, residing at Bowling Green, in the county of De Soto and State of Florida, have invented certain new and useful Improvements in Direction-Indicators; and I do hereby declare the following to be a full, clear, and exact description of the invention, such as will enable others skilled in the art to which it appertains to make and use the same.

My invention relates to signals or direction indicators for automobiles or other vehicles and resides in the provision of a simple and effective device that may be easily operated by the driver of the vehicle to which it is attached to indicate to other vehicles whether or not a right or left turn is to be made or the vehicle is to stop.

Another object is to provide a device of the character described that is constructed to form a dummy figure including head, body legs and arms, the arms being hinged and arranged to act as semaphores and each being provided with a light so that the device will operate effectively at night.

Another object is to provide novel means for electrically connecting and hingedly securing the arms of the dummy to the body thereof in such manner that the semaphore like operation of the arms is properly had and an effective signal produced.

Another object is to generally improve and simplify the construction and operation of such devices so as to render them more practical, and reliable and efficient in operation without materially increasing the cost of manufacture thereof.

The above and additional objects are accomplished by such means as are illustrated in the accompanying drawings, described in the following specification and then more particularly pointed out in the claims.

With reference to the drawings, wherein I have illustrated the preferred embodiment of my invention as it is reduced to practice, and throughout the several views of which similar reference numerals designate corresponding parts, Figure 1 is a front elevation of my improved device showing it as it would appear when ready for attachment to an automobile or like vehicle. Fig. 2 is a vertical sectional view taken through my improved device showing the electrical wiring diagram therefor and the operating means for moving the arms into and out of signal-

ing position. Fig. 3 is an enlarged detail vertical sectional view taken through one of the solenoids of the operating means. Fig. 4 is an enlarged detail perspective view of a part of the operating means and the hinge for connecting the arms to the body showing a fragmentary portion of the arm connected with the operating means therefor, and the light carried by the arm in diagrammatic relation thereto, Fig. 5 is a vertical sectional view taken through the hinge and connecting means, Fig. 6 is a detail top plan view of the slidable contact switch, and Fig. 7 is a longitudinal vertical sectional view taken through the sliding contact switch.

Referring to the drawings by characters of reference, 1 designates as an entirety the body of my improved device, which body is shaped as a manikin and comprises a hollow body, legs 2, and arms 3 which are also hollow. The arms 3 are hinged to the body. A head is carried by the body and it will thus be seen that the device when placed upon an automobile or like vehicle either at the front or rear will attract attention and prove effective as a signal. The legs of the figure or body 1 are secured in any suitable manner, not shown, to the vehicle to which the device is to be attached. Electric lamps 4 and 5 are carried at the end of the arms 3 and are provided to make the device effective at night.

As a means for hingedly connecting the arms 3 to the body, I provide elongated hinge leaves 6 that are secured by suitable fastening elements in substantially upright position within the body and at a point adjacent to the arm-pits thereof. Extending outwardly from and carried by the upper ends of the leaves 6 are divergent arms 7 that are provided with rolled ears 8 at their outer ends, which ears are disposed within the arms 3. Hinge pins 9 are inserted transversely through the arms 3 at the inner end thereof and through the ears 8 and hingedly connect the arms with the body in such manner that the arms may be moved upwardly and downwardly freely.

I provide means for operating the arms which comprises a pair of solenoid magnets 10. The magnets 10 are placed within the upper parts of the leg portions 2 of the body 1, said leg portions being filled with wax or some other suitable material so as to hold the solenoids 10 in approximately vertical position.

Vertically slidable armatures 11 are carried by the magnets 10. Rods 12 are secured to the inner ends of the arms 3 and extend into the body 1 to a point over and above the solenoids 10. Links 13 connect the rods 12 with the armatures 11, thus when the solenoids are energized, a downward pull is communicated to each of the rods 12 by means of the armatures 11 and links 13, and the arms 3 are moved outwardly into approximately horizontal position as shown in dotted lines in Fig. 1.

The electrical circuit for the device includes a battery or other suitable source of current 14 that is connected with sliding contact switches 15 and 16 by means of a conductor 17. Conductors 21 and 22 lead respectively from the switches 15 and 16 to the solenoids 10 and running from the solenoids 10 upwardly through the body are wires 23 and 24 that connect with the lower ends of the hinged leaves 6. The hinge leaves 6 and co-operating parts act as conductors and conductors 25 and 26 lead from the hinge leaves 6 to the lamps 4 and 5 respectively in the ends of the arms 3.

Mounted upon the hinge leaves 6 are contact plates 27 that are provided with outwardly directed upper ends 28. The contact plates 27 are insulated from the leaves 6 by means of suitable insulation 29. Tubular contact members 30 are mounted upon the hinge pins between the rolled ears 8 and are engaged by the outwardly directed terminals 28 of the plates 27, said plates 27 being of spring metal thus positively contacting with the contact members 30. Suitable insulation material 31 insulates the contact members 30 from the hinge pins 9. Conductors 32 are connected with the contact members 30 which are rotatably mounted upon the pins 9 with the lamps 4 and 5 and conductors 33 and 34 are connected with the plates 27 and with a conductor 20 which connects with the battery 14.

By operating the switch 15 the solenoid on the right side of the body and connected with the arm carrying the light 4 will be operated and cause the arm 3 to be moved into signaling position and the lamp 4 to illuminate. When a left turn is completed the switch 16 is operated closing the circuit for the lamp and solenoid on the left side of the body.

The switches 15 and 16 are identical as to construction and it is thought that only one of them need be described. The switch is best illustrated in Figs. 6 and 7 of the drawings. Each of the switches comprises a base plate 35 which is formed with a longitudinal slot 36. A fixed contact plate 37 is secured to the under face of the base plate at one end thereof and is disposed in alignment with and beneath the slot 36. An

insulation strip 38 is interposed between the plate 37 and the plate 35 to insulate the plate 37 from the plate 35. A spring metal contact plate 39 is secured as at 40 to the outer end of the plate 35 underneath said plate and is insulated therefrom. This contact plate 39 is provided with a downwardly curved free end 40 that is normally spaced from the contact 37. A slideable push button 41 is mounted upon the contact plate 39 and within the slot 36. The push button 41 may be pushed at any point in its sliding extent so as to cause the portion 40 of the plate 39 to contact with the stationary contact plate 37 and is provided with annular flange 42 that engages under the plate 35 so as to prevent said push button 41 from becoming accidentally deranged. The upper surface of the push button is disposed above the plane of the plate 35. The plate 35 is bowed centrally of its ends so as to provide an upwardly and inwardly inclined portion 43 and is formed with an offset portion 44. The switch members 15 and 16 are placed preferably upon the dash board of the vehicle to which the device is attached and so that they may be operated by the driver of the vehicle. When the push buttons 41 are moved upwardly to the highest point on the base plate 35, the contact members 39 and 37 are held in engagement with one another and the arm 3 will remain in signaling position. When it is desired to operate the arms simultaneously, both switches 15 and 16 are operated.

In practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as claimed.

What is claimed is:—

1. In a direction indicator, the combination with a hollow body to be secured to a vehicle of arms hinged to the body, means to move the arms into and out of signaling position, means to hingedly secure the arms to the body comprising hinge leaves secured within the body and extending into the arms, said arms and body being hollow, ears carried by the portions of the leaves that extend into the arms, hinge pins inserted through the arms and ears, an electrical circuit, electric lamps carried at the outer ends of the arms and connected in the circuit, and means carried by the hinge leaves and hinge pins to establish electrical connection between the lamps and circuit.

2. In a direction indicator comprising a hollow body to be attached to a vehicle, said body being provided with openings therein, a pair of elongated hinged leaves secured within said body adjacent said opening, outwardly converging arms secured to said hinge leaves and extending exteriorly of said body, said arms bent to form ears on the outer end thereof, arms provided within 10 adapted to pass through said ears and hingedly support said arms to the body, illuminating means carried at the outer end of each of the arms, an electrical circuit, solenoids mounted within the hollow body and operably connected with the circuit, rods rigidly secured to the arms and extending inwardly into the hollow body and links operably connected with the solenoids and the arms whereby when the solenoids are energized, the arms will be moved into 20 extended position.

In testimony whereof I affix my signature in presence of two witnesses.

CLAUD A. REESE.
